UNITED STATES PATENT OFFICE.

FRANK H. WAITE AND GEORGE W. DAVEY, OF LONG ISLAND CITY, NEW YORK.

FURNACE CONSTRUCTION.

Application filed November 27, 1925. Serial No. 71,686.

Our invention relates to furnace walls and the circulation of air therein, wherein there are a plurality of circulations of air employed in addition to the air supplied by a blower in the usual way, one of said circulations being through the front wall directed under the grate of the stoker and another directed into the smoke box or back of the bridge wall.

10 Our invention not only contemplates the combinations of air circulations by natural or stack draft combined with forced draft, but a circulation induced by an injective action in combination with other circulations 15 directed under the grate of a stoker, in addition to air supplied by a blower in the usual way.

This is accomplished by utilizing the heat transfer function of our air cooled furnace 20 blocks, specifically illustrated, described and claimed in our application bearing Serial Number 55,752, filed September 11th, 1925.

We also utilize the horizontal and vertical 25 expansion means illustrated, described and claimed in our pending application filed October 15th, 1925, bearing Serial Number 62630.

One object of our invention is to circulate 30 air in the front wall by stack or natural draft suction in combination with other circulations throughout the side walls and a forced draft means.

Another object of our invention is to circulate 35 air in the front wall by an injective action of a forced draft means in combination with other circulations throughout the side walls and a forced draft means.

Other valuable features of our invention 40 and the unique application of the circulations are described, pointed out and illustrated in the accompanying drawings wherein like numerals indicate like parts, and in which:

Figure 1 is a longitudinal section of a wa- 45 ter tube boiler stoker furnace.

Figure 2 is a partial front elevation of Figure 1.

Figure 3 is a longitudinal section of a wa- 50 ter tube boiler stoker furnace illustrating a modification of the invention.

Figure 4 is a partial front elevation of Figure 3.

Figure 5 is a partial plan in section of Figure 1.

Figure 6 is a partial plan in section of Figure 3.

Figures 1, 2 and 5 illustrate a water tube boiler furnace consisting of a front wall 1, side walls 2 and 3, bridge wall 4, water tubes 5, a drum 6, an angular baffle 7, a vertical baffle 8, a gas outlet 9, a clean out opening 10, a grate 11 the combustion chamber 12, a stoker mechanism 13, a coal hopper 14, a blower or fan 15 and a wind box 16.

There are four separate and distinct circulations of air throughout the furnace, illustrated in Figures 1, 2 and 5, two of which circulate through the furnace walls, cooling the interior of the walls or the superimposed broken jointed air cooled blocks that make up the major portion of the furnace lining; and the air preheated in transit throughout the said walls is utilized as preheated air for a more complete or perfect combustion of the materials of combustion.

In the third or well known forced draft circulation, the air from the blower 15, driven by the motor 17 and belt 18 is forced into the wind box 16, passes under the grate 11 through the elbow 19, provided with a controlling damper 20, to the combustion chamber 12, through the fuel on the grate 11, thence upwardly around the tubes 5, drum 6, over baffles 7, downwardly around tubes 5, under baffles 8, upwardly around tubes 5, around drum 6, through the gas outlet 9 to the stack.

In the first circulation illustrated in Figures 1, 2 and 5, the air in the front wall, baffled at 25 and 26, enters the horizontal flues 21 of the blocks 22, provided with vertical flues 23, through inlets 24, each of which is provided with a damper 27, having a slide 28 controlling the volume of air entering said inlets.

The air in this front wall 1, preheated in transit in its downward passage throughout the blocks 22, flowing in a direction opposite to the flaming gases in the combustion chamber 12, is directed upwardly under the grate 11 by the elbow 29 and there is a suction induced in this elbow 29 by the forced draft pressure hereinbefore described, which co-operates with the stack pressure or suction in operating this circulation.

The second aforesaid circulation in reference to Figures 1, 2 and 5 is the circulation throughout the superimposed, broken jointed walls 2 and 3 built up in part of air cooled refractory blocks 22, and these walls are provided with horizontal expansion means 30 and 31 and vertical expansion means 32

as well as the horizontal expansion spaces 33, 34, 35 and 36 in walls 2 and 3 respectively.

The air entering the horizontal flues 21 of the wall 2 through flues or ducts 37, each provided with a damper 27 having a slide 28 controlling the volume of air admitted thereto, passes throughout the horizontal and vertical flues 21 and 23 in the wall 2 in a substantially horizontal direction, flowing at right angles to the flow of flaming gases within the combustion chamber 12, into the expansion space 34 which also acts as a manifold for all the air preheated in transit throughout said wall, from whence the preheated air is directed into a common manifold 38 by the flue 39 within the bridge wall 4.

The air circulating in wall 3 enters the horizontal and vertical flues 21 and 23 respectively, through a multiplicity of ducts 40, each of which is provided with a damper 27, having a slide 28 controlling the volume of air admitted to each of said ducts 40, passes in a substantially horizontal direction at right angles to the flow of flaming gases within the combustion chamber 12, into the expansion space 35 which acts as a common manifold for said air preheated in transit throughout said blocks 22, from whence the preheated air is directed into the common manifold 38 for both walls 2 and 3 by the duct or flue 41.

The preheated air thus collected in the manifold 38 common to both walls 2 and 3, is directed to flow back of the bridge wall 4 by ducts 42 and 43 of equal area in cross section and duct 44 of a greater area in cross section, from whence it passes upwardly around the tubes 5 and drum 6 through the gas outlet 9 into the stack.

The second circulation is within the wall 2, passing throughout the wall within the ducts 21 and 23 into the common manifold 38 and from thence to the stack as hereinbefore described.

The third circulation is within the wall 3, passing throughout the wall within the ducts 21 and 23 into the common manifold 38 and from thence to the stack as hereinbefore described.

In the fourth circulation the air from the blower 15 is forced into the wind box 16 under the grate 11, directed thereto by the elbow 19 having a volume controlling damper 20, into the combustion chamber 12 from whence it passes upwardly around the tubes 5 and drum 6, downwardly over baffle 7, around tubes 5, under baffle 8, upwardly around tubes 5, through gas outlet 9 into stack.

Thus the air preheated in transit throughout the front wall 1, circulating by the combined induced action of the blower and draft of the stack is utilized for a more complete

combustion of the fuel within the combustion chamber 12.

The air preheated in transit throughout each side wall is directed into the second or third pass behind the bridge wall and is not utilized in the combustion chamber at all.

In Figures 3, 4 and 6, there are illustrated five different and distinct circulations of air within a furnace, four of which circulate throughout the side and front walls, cooling the interior of the walls or the superimposed broken jointed air cooled refractory blocks that make up, in part, the side walls; and the air preheated in transit throughout the said walls is utilized for more complete combustion of the fuel within the combustion chamber 12.

The fifth circulation is precisely the same as the third hereinbefore described, having similar controlling means and flow.

In the first circulation the air from the blower 15 passes into the wind box 16, under the grate 11, through the elbow 19 provided with a volume controlling damper 20 to the duct 45 and into the common manifold 46 of side wall 3, flowing upwardly in a direction parallel to the flow of flaming gases within the combustion chamber 12, and is directed to flow evenly throughout the wall 90 toward the front wall by the baffles 49, 50 and 51 into an expansion space acting as a common manifold 36 from whence the air flows in a substantially horizontal direction 100 at right angles to the flow of flaming gases within the combustion chamber 12 throughout the horizontal and vertical passages 21 and 23 in the front wall 1, and is directed to flow evenly throughout the said wall 1 by the baffles 52 and 60 downwardly into a common manifold 54 from whence the air preheated in transit throughout the said wall of air cooled blocks is directed into a conduit or flue 55 terminating in a reduced end 56 which is centrally located within the elbow 19 in parallel relation thereto and to the flow of air under pressure therein from the blower 15.

The air thus preheated is circulated by the injective action of the forced draft from the blower upon the reduced conduit in parallel relation to the blower elbow or an equivalent and the flow of air therein.

A portion of this preheated air flows upwardly through the grate 11 into the combustion chamber 12 around tubes 5 and drum 6, over baffle 7, downwardly around tubes 5 under baffle 8, upwardly around tubes 5 and drum 6 into the gas outlet 9 to the stack.

Another portion of this air enters the duct 45 and circulates throughout the walls 3 and 1 as hereinbefore described, continues to circulate in this cycle and composes the second circulation.

In the third circulation the air from the blower 15 passes into the wind box 16, under the grate 11, through the elbow 19 provided with a volume controlling damper 20 into the common manifold 48 of the side wall 2 by the duct 47, flowing upwardly in a direction parallel to the flow of flaming gases within the combustion chamber 12, and is directed to flow evenly throughout the wall 10 toward the front wall by the baffles 57, 58 and 59 into an expansion space acting as a common manifold 33 from whence the air flows in a substantially horizontal direction at right angles to the flow of flaming gases 15 within the combustion chamber 12 throughout the horizontal and vertical passages 21 and 23 in the front wall 1, and is directed to flow evenly throughout the said wall 1 by the baffles 53 and 60, downwardly into a common manifold 54, from whence the air preheated in transit throughout the said walls of air cooled blocks is directed into a conduit or flue 55, terminating in a reduced end 56 which is centrally located within the elbow 19 in parallel relation thereto and to the flow of air under pressure therein from the blower 15.

The air thus preheated is circulated by the injective action as hereinbefore described in 20 the first circulation and likewise a portion of this air passes throughout the furnace in a like manner and this constitutes the third circulation.

The fourth circulation is one similar to the 25 second only in wall 2 and 1 entering manifold 48 through the duct 47.

In the fifth circulation the air from the blower passes into the wind box 16 under the grate 11 through the elbow 19 having a 30 volume controlling damper 20, through the grate 11 and the fuel thereon into the combustion chamber 12, upwardly and around tubes 5 and drum 6, downwardly over baffles 7, around tubes 5 under baffles 8, upwardly around tubes 5 and drum 6 into gas outlet 9 to stack.

The side walls are provided with horizontal expansion means 30 and 31, vertical expansion means 32 and horizontal expansion 35 spaces 33, 34, 35 and 36.

Having thus described and illustrated the preferred embodiment of our invention we do not desire to limit ourselves to the exact subject matter pertaining to the specific circulations and combination thereof, as modifications may be made without departing

from the spirit of the invention or the scope of the claims.

We claim:-

1. In a furnace structure, the combination 60 of refractory front and side walls having air passages therein, a stoker grate in the furnace chamber, an outlet for the products of combustion in an upper part of the chamber, a bridge wall having air passages therein, 65 baffle means directing the products of combustion from the outlet across and back of the bridge wall, ports from the bridge wall passages out through the rear of said wall, air feeding means below the grate, air inlet 70 means to the front wall passages, air conducting means leading from said passages to a point beneath the grate within the influence of the air from said feeding means, air inlets for the side wall passages, and a communicating duct between the passages of each side wall and the passages of the bridge wall. 75

2. In a furnace structure, the combination 80 of refractory walls composed of blocks having air passages therein, said walls substantially defining the combustion chamber, means for admitting fuel to said chamber, an offtake for the products of combustion, air inlets to the passages of a wall, air ports 85 from the passages of another wall into the furnace chamber, and a combined air duct and expansion space for the refractory blocks said slot duct connecting the passages of the wall having inlets to the passages of 90 the wall having ports into the chamber.

3. The combination with a furnace having refractory front and side walls, a grate, means for feeding fuel, air feeder means, and an offtake for the products of combustion; of air passages in the walls, baffle means in the front wall dividing said passages into a plurality of circulatory systems, baffles in the side walls spaced to distribute uniformly the air flowing through said 100 walls, air inlet means to said side wall passages opening under the grate and adapted to receive air from the feeder, and air outlet means from the front wall passages positioned in the flow of air from the feeder to 105 deliver heated air beneath the grate.

Signed at Long Island City in the county of Queens and State of New York this 24th day of November A. D. 1925.

FRANK H. WAITE.
GEORGE W. DAVEY.

In the third circulation the air from the blower 15 passes into the wind box 16, under the grate 11, through the elbow 19 provided with a volume controlling damper 20 into the common manifold 48 of the side wall 2 by the duct 47, flowing upwardly in a direction parallel to the flow of flaming gases within the combustion chamber 12, and is directed to flow evenly throughout the wall 10 toward the front wall by the baffles 57, 58 and 59 into an expansion space acting as a common manifold 33 from whence the air flows in a substantially horizontal direction at right angles to the flow of flaming gases 15 within the combustion chamber 12 throughout the horizontal and vertical passages 21 and 23 in the front wall 1, and is directed to flow evenly throughout the said wall 1 by the baffles 53 and 60, downwardly into a common manifold 54, from whence the air pre-heated in transit throughout the said walls of air cooled blocks is directed into a conduit or flue 55, terminating in a reduced end 56 which is centrally located within the elbow 19 in parallel relation thereto and to the flow of air under pressure therein from the blower 15.

The air thus preheated is circulated by the injective action as hereinbefore described in 20 the first circulation and likewise a portion of this air passes throughout the furnace in a like manner and this constitutes the third circulation.

The fourth circulation is one similar to the second only in wall 2 and 1 entering manifold 48 through the duct 47.

In the fifth circulation the air from the blower passes into the wind box 16 under the grate 11 through the elbow 19 having a 40 volume controlling damper 20, through the grate 11 and the fuel thereon into the combustion chamber 12, upwardly and around tubes 5 and drum 6, downwardly over baffles 7, around tubes 5 under baffles 8, upwardly around tubes 5 and drum 6 into gas outlet 9 to stack.

The side walls are provided with horizontal expansion means 30 and 31, vertical expansion means 32 and horizontal expansion 50 spaces 33, 34, 35 and 36.

Having thus described and illustrated the preferred embodiment of our invention we do not desire to limit ourselves to the exact subject matter pertaining to the specific circulations and combination thereof, as modifications may be made without departing

from the spirit of the invention or the scope of the claims.

We claim:

1. In a furnace structure, the combination of refractory front and side walls having air passages therein, a stoker grate in the furnace chamber, an outlet for the products of combustion in an upper part of the chamber, a bridge wall having air passages therein, baffle means directing the products of combustion from the outlet across and back of the bridge wall, ports from the bridge wall passages out through the rear of said wall, air feeding means below the grate, air inlet means to the front wall passages, air conducting means leading from said passages to a point beneath the grate within the influence of the air from said feeding means, air inlets for the side wall passages, and a communicating duct between the passages of each side wall and the passages of the bridge wall.

2. In a furnace structure, the combination of refractory walls composed of blocks having air passages therein, said walls substantially defining the combustion chamber, means for admitting fuel to said chamber, an offtake for the products of combustion, air inlets to the passages of a wall, air ports from the passages of another wall into the furnace chamber, and a combined air duct and expansion space for the refractory blocks said slot duct connecting the passages of the wall having inlets to the passages of the wall having ports into the chamber.

3. The combination with a furnace having refractory front and side walls, a grate, means for feeding fuel, air feeder means, and an offtake for the products of combustion; of air passages in the walls, baffle means in the front wall dividing said passages into a plurality of circulatory systems, baffles in the side walls spaced to distribute uniformly the air flowing through said walls, air inlet means to said side wall passages opening under the grate and adapted to receive air from the feeder, and air outlet means from the front wall passages positioned in the flow of air from the feeder to deliver heated air beneath the grate.
